UNITED STATES PATENT OFFICE.

JAMES B. HAMBLIN, OF JACKSON, MICHIGAN, ASSIGNOR OF ONE-HALF TO
WILLIAM L. HOBART, OF SAME PLACE.

APPARATUS FOR STRAIGHTENING RAKE-TEETH.

SPECIFICATION forming part of Letters Patent No. 244,597, dated July 19, 1881.

Application filed April 21, 1881. (No model.)

To all whom it may concern:

Be it known that I, JAMES B. HAMBLIN, of Jackson, Jackson county, Michigan, have invented an Improvement in Machines for Straightening Cast-Steel Rakes, of which the following is a specification.

The nature of this invention relates to the construction of a device particularly designed for pressing and straightening the teeth of cast-steel garden-rakes; and the invention consists in the peculiar construction and arrangement of the various parts, all as more fully hereinafter set forth.

Figure 1 shows the upper and lower dies in their relative positions as when attached to a power-press. Fig. 2 is a cross-section of the same.

In the accompanying drawings, which form a part of this specification, A represents a bed-piece, of cast-iron, and is fastened by bolts passing through slots *a* therein to the base of the power-press, the slots allowing of adjustment.

B is a dowel-plate, of wrought-iron. C is the lower die-plate, of cast-steel, and is fastened to the bed-piece A, together with dowel-plate B, by the bolts *c* passing up from the bottom of the bed-piece A.

D represents a series of small dies in front of the die-plate C, and they are held in place by dowels or pins *c'* passing downward through tenons *d* of the dies into the bed-piece.

E is a wing-die, similarly secured to place, the movement of the wing-die being limited by the pin *e*, while the movement of the dies D is limited between said wing-die and the projection *f* of the bed-plate.

An arm, F, projects from the front of the bed-plate, to which arm is secured the comb G. A recess, H, is formed in the bed-plate A, immediately beneath the dies D, through which the scale pressed from the rake falls, and in each end of the die is formed a flaring slot, I, to receive the tang or shank of the rake while being pressed.

The upper die or head-piece is bolted to the working head of the power-press by bolts *g* passing through the plate J.

To the lower face of the plate J are attached the steel dies K and L, the latter one being 50 adjustable, shim-pieces M of the desired thickness being interposed between them. The die L is provided with a face, N, which projects slightly beyond the face of the die K.

A spring-blade, R, having its lower end extending below the face of the die, is bolted at its upper end to the vertical spring-arm O of the adjustable arm P.

In practice the parts are properly secured to a power-press, the spring-blade R being in 60 such a position that it will impinge, in descending, against the outer face of the wing-die E, which is beveled upon such outer face, as at *h*, thereby causing such wing-die E to be pressed laterally the desired distance.

The rake to be operated upon is heated a little more than half its length, and is placed flatwise upon the lower die, with the shank downward and in the slot I, as shown in dotted lines, Fig. 1, and one operation of the upper die is given upon it, so as to bring all the teeth operated on to the same horizontal plane. When this is done, and should the teeth be too crooked to be introduced between the dies D, they can easily be straightened by drawing 70 them through the comb G, beginning as near the back of the teeth as possible. The teeth can now be introduced, one between each of the dies D and *a'*. Single downward movements of the press being given, the spring R, descending, will, by striking the wing-die E, exert a lateral pressure upon the dies D, forcing them toward the rigid projections *f*, and thereby flatten the teeth inserted between them to any desired degree, and at the same time the face of 80 the die K will straighten the back of the rake edgewise.

By heating the remaining portion of the rake, reversing its position, and repeating the operation above described the other portion of the 85 rake may likewise be straightened.

What I claim as my invention is—

1. In a device for straightening and pressing rake-teeth, the swaging-dies D, in combination with the wing-die E and spring R of 90 the upper die, substantially as described.

2. In a device for straightening and pressing rake-teeth, a series of swaging-dies operated by the action of a spring or arm attached to the upper die, in combination with the lower die, C, and the upper dies, K and L, substantially as set forth.
3. In a device for straightening and pressing the teeth of cast-steel rakes, and in combination with the dies C, K, L, and D, the comb to G, substantially as specified.
4. A device for straightening and pressing rake-teeth, consisting of the bed-piece A, dies C D E K L, and comb G, arm F, spring R, slot I, and recess H, substantially as and for the purposes described.

JAMES B. HAMBLIN.
